US0D1060945S

(12) **United States Design Patent** (10) Patent No.: **US D1,060,945 S**
 Siegienczuk (45) Date of Patent: ** Feb. 11, 2025

(54) **TACTICAL CLOTHING**

(71) Applicant: **CORE M MIESZCZAK SPÓŁKA KOMANDYTOWO-AKCYJNA, Wroclaw (PL)**

(72) Inventor: **Piotr Siegienczuk, Wroclaw (PL)**

(**) Term: **15 Years**

(21) Appl. No.: **35/519,059**

(22) Filed: **Jul. 24, 2023**

(80) **Hague Agreement Data**

Int. Filing Date: **Jul. 24, 2023**

Int. Reg. No.: **DM/233047**

Int. Reg. Date: **Jul. 24, 2023**

Int. Reg. Pub. Date: **Nov. 17, 2023**

(51) **LOC (15) Cl. 02-02**

(52) **U.S. Cl.**

USPC **D2/857**

(58) **Field of Classification Search**

USPC D2/719, 828, 836, 839, 853, 857, 861, D2/863, 864

CPC A41D 27/207
